SHAMPOO CAPE

Flora H. Ellinger, Chicago, Ill.

Application March 1, 1943, Serial No. 477,566

5 Claims. (Cl. 4—159)

My invention relates generally to improvements in appliances for facilitating treatment of the hair and scalp, and relates more particularly to improvements in the construction and operation of capes or similar protectors adapted to be used by individuals having their hair shampooed, cut or otherwise treated.

An object of the present invention is to provide an improved shampoo cape or the like, which is simple in construction and highly effective in use.

Some of the more important specific objects and advantages of the invention, are as follows:

To provide a new and useful appliance for facilitating washing, shampooing, and rinsing of the hair of individuals, while positively protecting the persons wearing the appliance against spray and splashing.

To provide an improved liquid-proof cape or protector adapted to be worn by persons receiving hair and scalp treatments, and which will prevent soapy water and other treating liquid from reaching the bodies of the individuals using the cape.

To provide an improved device for permitting effective shampooing of relatively long human hair and for facilitating rinsing of such hair, while the individual receiving the treatment may remain disposed in a comfortable position.

To provide an improved shampoo cape or the like which may either be provided with simple and adjustable means for suspending the same from a support such as a chair occupied by the wearer, or with protectors for the ears of the user, or used without such support and protectors.

To provide a simple portable protective covering for the shoulders and back of a person receiving head treatments of various kinds, which can be used over and over, and which may also be manufactured and sold at moderate cost.

These and other specific objects and advantages of my invention will be apparent from the following detailed description.

A clear conception of the several features constituting the present improvement, and of the mode of constructing and of using my improved shampoo cape assembly, may be had by referring to the drawing accompanying and forming a part of this specification wherein like reference characters designate the same or similar parts in the various views.

Fig. 1 is a side elevation of one of the improved shampoo capes with the special supports and ear protectors applied thereto; showing the

device associated with an individual, a chair and a wash basin, all associated parts being illustrated in dot-and-dash lines;

Fig. 2 is a front and side perspective view of the cape alone with the special supports and ear protectors removed; and

Fig. 3 is a fragmentary section through one of the shoulder portions of the cape, showing the ear protectors applied to the neck saddle thereof.

Although the invention has been shown and described herein as being especially applicable to portable water-proof capes for facilitating the operation of shampooing human hair, it is not my desire or intent to thereby unnecessarily restrict the scope or to unduly limit the utility of the improved appliance.

Referring to the drawing, the improved shampoo cape shown therein by way of illustration, comprises in general a neck engaging socket or saddle portion 5 having its rear wall 6 shaped to snugly fit the base of the skull or rear neck and head portion of an individual 7, while its front portion is provided with an integral releasable retaining strap 8 having several slots 9 cooperable with a fastener 10 so as to hold the saddle portion 5 in place; a laterally and rearwardly extending and depending drain apron 11 formed integral with the saddle portion 5 and having integral opposite side ridges 12 extending from the lower end thereof upwardly over the shoulder portions thereof and merging with the opposite sides of the neck saddle; and forwardly and downwardly extending shoulder protecting extensions 13 also formed integral with the saddle portion 5 and apron 11.

The entire one-piece or unitary cape structure is preferably formed of rubber or other relatively stiff but flexible water-proof material which is adapted to comfortably conform with the neck, shoulders and back of the individual user, and the neck strap 8 should be so formed as to permit snug application of the saddle portion 5 to the necks of different individuals 7.

The shoulder flaps or protecting extensions 13 and the upper portion of the apron 11 should be sufficiently wide to properly cover and conceal the shoulders and chest of the individual 7, and the apron 11 should be sufficiently extensive to provide a proper support for long hair 14 and to overlap the rim 15 of a wash-basin or sink when the cape has been applied as shown in Fig. 1. The marginal ridges 12 of the apron 11 should also be of sufficient height to provide a barrier 55 for preventing liquid from flowing over the

shoulders of the wearer of the cape, and over the opposite sides of the apron 11, and the lower edge of the apron 11 should be devoid of ridges or projections which might interfere with free drainage of liquid therefrom.

Since the cape if properly and durably constructed, may be relatively heavy, it might be desirable to provide an auxiliary support for the cape assembly. Such support may be readily produced by forming lugs 16 on the underside of the apron 11 as shown in Figs. 1 and 2, and by providing adjustable supporting rods or bars 17 co-operable with these lugs 16 and with suspension brackets 18 associated with the back of a chair 19 upon which the individual 7 would normally be seated while undergoing head treatment. The upper ends of the bars 17 may be bent for detachable insertion within openings in the lugs 16, while the lower straight ends of these bars 17 may be adjustable in holes in the brackets 18 and secured in adjusted positions by means of screws 20. The brackets 18 may be adjustably clamped to the chair back by means of thumb screws 21, thus providing supports for the cape which can be readily adjusted to meet varying conditions.

It may also be desirable in some cases, to provide protection for the ears of the individual 7 utilizing the cape assemblage, and for this purpose I have also provided a pair of removable ear protectors 22 suspended from the saddle portion 5 by means of flexible reeds 23, and detachably secured to the collar saddle with the aid of snap fasteners 24, as shown in Figs. 1 and 3. These ear protectors 22 may be formed of water-proof material, and are shaped as pockets adapted to hook over the individual's ears, and they may obviously be readily removed if not desired. The suspension reeds 23 may either be formed of stretchable or elastic material, or they may be adjustable in length so as to aid in enhancing the comfort of the user.

The improved shampoo cape may obviously be used as shown in Fig. 2, without the auxiliary support and without utilizing the ear protectors 22, but the entire assemblage may obviously be quickly assembled as shown in Fig. 1, or the accessories may be just as quickly removed. During normal use of the improved shampoo cape, and assuming the device to have been completely assembled and applied as shown in Fig. 1, the hair 14 of the individual 7 may be effectively shampooed, washed, and rinsed while all liquid will be compelled to flow away from the head of the person receiving the treatment, by virtue of the formation of the neck saddle 5, apron 11, ridges 12 and ear protectors 22. The extensive apron 11 will permit the hair 14 to be disposed thereon during washing and rinsing, and the apron 11 will obviously conduct drainage liquid directly into the basin over the rim 15. The lower portions of the ridges 12 cooperate with the apron 11 to provide a drainage trough, and the uppermost portions of the ridges 12 will prevent liquid from flowing over the shoulders of the individual 7, while the extensions 13 will prevent splash liquid from dropping on the individual's clothes. The formation of the neck saddle 5 and the provision of the adjustable securing strap 8, will obviously permit application of the cape so that no liquid can escape along the neck of the individual, and the pocket formation of the ear protectors 22 will obviously most effectively protect the ears from ingress of liquid. By manipulating the screws 20, 21, the cape may be readily adjusted to comfortably fit individuals of various heights

and to relieve the weight, and as previously indicated both the auxiliary support and the ear protectors 22 may be readily removed to permit use of the cape in the stripped form shown in Fig. 2.

5 From the foregoing detailed description of the construction and use of the cape, it will be apparent that my present invention provides a simple portable protective device for facilitating the treatment of the hair 14 or scalp of an individual 10 7, and while the improved appliance is especially useful for shampoo purposes, it can also be advantageously used when cutting hair or otherwise treating the scalp and head. The improved cape can be readily constructed of water-proof 15 material so as to positively prevent passage of liquid therethrough, and the formation of the neck saddle 5, apron 11 and extensions 13 insures maximum protection of the individual, and additional protection can obviously be obtained by 20 utilizing the ear protectors 22. The improved unitary assemblage can moreover be suspended from an ordinary chair 19 and by virtue of its portability can be carried to various locations of 25 beauty parlors or barber shops, thus making its use extremely flexible and avoiding necessity of having the individuals undergoing treatment assume uncomfortable positions especially during the final hair rinsing operations. The improved cape by virtue of its flexibility and the formation 30 of the apron 11, fits into any type of sink or wash basin that will take care of the drainage water and which is convenient for the operator, and the device can be manufactured and sold at moderate cost and has proven highly successful 35 and satisfactory in actual use.

It should be understood that it is not desired to limit this invention to the exact details of construction or to the precise mode of use, herein shown and described, for various modifications 40 within the scope of the appended claims may occur to persons skilled in the art.

I claim:

1. A shampoo cape, comprising, a neck engaging saddle, and an apron extending laterally and rearwardly away from said saddle and being provided with ridges for conducting liquid downwardly therealong, said apron being curved both laterally and longitudinally to snugly engage the shoulders of the wearer.

45 2. A shampoo cape, comprising, a neck engaging saddle, an apron extending laterally and rearwardly away from the saddle, said apron being curved to snugly engage the wearer's shoulders and having liquid barriers extending outwardly away from said saddle and downwardly 55 along the opposite sides of the apron, and downwardly curved shoulder protecting extensions projecting forwardly away from the upper portion of said apron on opposite sides of the saddle.

60 3. A shampoo cape, comprising, a neck engaging saddle, an apron extending laterally and rearwardly away from the saddle, said apron being curved both laterally and longitudinally to snugly engage the shoulders of the wearer and having liquid barriers extending outwardly away from said saddle and downwardly along the opposite sides of the apron, and downwardly curved shoulder protecting extensions projecting forwardly away from the upper portion of said apron 65 on opposite sides of the saddle, said saddle and apron and barriers and extensions being formed integral with each other of waterproof material.

65 4. A shampoo cape, comprising, a saddle adjustable to snugly fit the neck of a wearer, a trough shaped liquid drainage apron depending 70 75 on opposite sides of the saddle, said saddle and apron and barriers and extensions being formed integral with each other of waterproof material.

from the rear of said saddle, and shoulder extensions projecting forwardly from the upper side portions of said apron and being curved to snugly engage the wearer's shoulders.

5. A shampoo cape, comprising, a saddle adjustable to snugly fit the neck of a wearer, a trough shaped liquid drainage apron depending from the rear of said saddle, and shoulder ex-

5 tensions projecting forwardly and downwardly from the upper side portions of said apron and being curved to snugly engage the wearer's shoulders, said saddle and said apron and said extensions being formed integral with each other of water-proof material.

FLORA H. ELLINGER.
